TUYÈRE STRUCTURE

Martin De Lin, Holland, Mich., assignor to
 Holland Furnace Company, Holland, Mich., a
 corporation

Application November 16, 1940, Serial No. 365,978

3 Claims. (Cl. 158—76)

My present invention relates to improvements in fluid fuel burners, and particularly to tuyère structures pertaining to fluid fuel burners as are employed in connection with heating furnaces for buildings, and wherewith fluid fuel, such as hydro-carbon oils, is employed as a base, and air, having oxygen as a major constituent, is employed and supplied to the oil in an atomized state as it is ejected from the burner nozzle, in order to promote proper combustion of the fluid fuel; and the objects of improvement are:

First, to provide a tuyère structure for fluid fuel burners that will cause the burner with which my improved tuyère is employed, to be more efficient in the consumption of fluid fuel than such burners not employing my tuyère structure.

Second, to provide a tuyère structure for fluid fuel burners that can readily be adjusted for bringing about the most complete combustion of the fuel burned.

Third, to provide a tuyère structure for fluid fuel burners that will be simple to construct.

Fourth, to provide a tuyère structure for fluid fuel burners that can be applied readily to burners of widely different types.

The above named objects and such other objects as may appear from a perusal of the following description, when the said description is taken in connection with the accompanying drawing, are attained by the structure disclosed by said drawing, in which:

Figure 1 is a side elevation view of a conventional fluid fuel burner housing, with a portion of the air discharge end broken away, in order to disclose in cross-section, my improved tuyère as applied to a burner housing.

Figure 2 is an end elevation view of my tuyère showing the parts thereof in their respective assembled positions.

Figure 3 is a plan view of the annular shim by which the tuyère structure is adjusted for position in relation to the atomizing nozzle.

Figure 4 is a plan view of my tuyère looking towards the air exit side thereof.

Throughout the several views of the drawing, similar numerals refer to similar parts and portions of my improved tuyère; and referring thereto—

Numeral 1 refers to a fluid fuel burner housing having therein an atomizing nozzle 2 and fuel ignition electrodes 3, and engaging the discharge end 4 of the housing 1, annular flange 5 which may be secured to the discharge tube 4 by any suitable means, but preferably by drive or

5 force fit; having extending axially therefrom, in-turned fuel exit flange 6 having at the junction with annular flange 5, shoulder 7 against which rests, when in the position shown in Figure 1, an annular tuyère diaphragm 8 having inwardly extending air deflector blades 9 each having a flat plane portion 10 extending transversely toward the axis of the diaphragm and a portion 11 in inclined relation to the flat plane portion 10 of and at each juncture of the several deflector blades is a semi-circular opening 12. Shims 13 consisting of thin sheet metal rings serve as adjusting means for the diaphragm 8 either towards the fuel atomizing nozzle 2 by inserting all of 15 the shims as shown in Figure 1 or away from it as required for producing desired combustion of the fuel removing one or more shims, or changing shims from one side of the diaphragm to the opposite side. In Figure 1 the shims 13 are shown 20 located between the end of the burner housing discharge and the shoulder 7 of the tuyère housing, in which position the diaphragm 8 is adjusted to its farthest position from the atomizer nozzle 2 and by placing the said shims between the shoulder 7 and the diaphragm, the 25 diaphragm will be in its nearest position to the atomizer nozzle, and by placing a portion of the shims, of which three are shown, at each side of the diaphragm, the diaphragm is adjusted to 30 intermediate position between the shoulder 7 and the end of the burner housing discharge end, thus it will be understood by placing the shims 13 at one or the other sides of the diaphragm 8 any required adjustment of the diaphragm in 35 relation to the burner may be had.

In the operation of a fluid fuel burner equipped with my improved tuyère structure, the burner having the usual means for generating pressure for ejecting fluid fuel, such as fuel oil, from an 40 atomizing nozzle, and a motor driven air blower for delivering air under pressure to the burner housing discharge, having therein an atomizing nozzle and having my improved tuyère structure partly inclosing the open end of the housing 45 discharge; the motor is put in operation, which in turn rotates the impeller of the blower, thereby delivering air under pressure to the discharge outlet of the burner housing, where the air is mixed with the atomized fluid fuel but not in 50 sufficient quantity for most efficient combustion of the fuel. This substantially complete mixing I accomplish by the use of my improved tuyère, that thoroughly mixes the constituents of the fuel as it passes through the tuyère, which as the 55 atomized fluid fuel is discharged from the dis-

charge nozzle spreads and is mixed with the air blown into the atomized fuel oil. The fuel mixture when the usual tuyère is employed is spotty and unduly rich in fuel oil, in the outer zone of the fuel column and rarer at its axial zone. By the use of my improved tuyère, the incompletely mixed fuel delivered to diaphragm 8 having flat portions 10 and inclined portions 11 is thoroughly mixed by being deflected inward toward the axis of the mixed fuel column or tuyère, by the inclined portion 11 of the blades 9, which imparts to the fuel column, cross-currents similar to those of a column of air striking the blade of a stationary screw propeller and thereby causing a thorough mixture of air and atomized oil, and it is the combination of the transversely deflected portion of air and the portion deflected from the inclined portions 11 of the blades 9 that produces a complete mixing of air and atomized fuel oil, and substantially complete combustion of the fuel with the exception of an outer layer like portion which is rare in fuel oil which is caused by the fuel mixture contacting the atmospheric air as it flows from the burner and by its forward moving contact with the atmosphere draws into the outer zone portion of the fuel additional air, and thereby causes eddy currents in the outer portion of the fuel mixture. In order to overcome the said eddy currents at the periphery of the combustion flame column I have provided holes 12 whereby a plurality of jets of the air are directed against the outer periphery of combustion flame column within the exit flange 6.

In the production of fluid fuel burners, discrepancies in dimensions are frequently encountered which cause poor combustion should the relation between the fuel atomizing nozzle and the fuel mixing tuyère be such as not to bring about the most efficient combustion of the fuel, I therefore have provided the plurality of thin ring shims 13, which may be placed at either side of the diaphragm 8 as the case may require to bring about a proper mixing of the fuel and higher efficiency of combustion.

Having described my present invention consisting of improvements in tuyère structures for fluid fuel burners, the rights which I desire are disclosed in the claims, as follows:

1. In a tuyère structure, a housing with a blower therein, an air tube extending therefrom, a liquid fuel atomizer nozzle adjacent the outlet

end of the tube; an annular member extending over the end of the air tube and having an inturned flange and a shoulder at the base of the said inturned flange, a diaphragm between the said shoulder and the end of the air tube and having an opening, said diaphragm having a plurality of air deflector blades each comprising a flat portion extending radially inward toward the axis of said tube and a curved portion 10 in inclined relation to the flat portion, and a plurality of annular ring like shims of thin metal at a side of the said diaphragm and between the end of the air tube and the shoulder of said annular member.

2. In a tuyère structure, a hollow housing with a blower therein, an air exit tube extending therefrom, a liquid fuel atomizer nozzle adjacent the open end of the air exit tube, an annular member encircling the end of the said air exit tube and having an inturned flange with a shoulder at the base of the inturned flange, a diaphragm held between the said shoulder and the open end of the air exit tube and having an opening and comprising a plurality of air deflector blades extending inwardly, each of said blades being separated from the adjacent blades by a semi-circular opening at their bases and each blade having a substantially flat portion extending transversely of the air exit tube and a portion extending from the said substantially flat portion in inclined relation to the axis of the tuyère and in the direction of the air flow therethrough.

3. In a tuyère structure, a hollow housing with a blower therein, an air exit tube extending therefrom, a liquid fuel atomizer nozzle adjacent the open end of the air exit tube, an annular member encircling the end of the said air exit tube and having an inturned flange with a shoulder at the base of the inturned flange, a diaphragm held between the said inturned flange and the open end of the air exit tube and having an opening and comprising a plurality of air deflector blades extending inwardly, each of said blades having a substantially flat portion extending transversely of the air exit tube and a portion extending from the said substantially flat portion in inclined relation to the axis of the tuyère and in the direction of air flow there- 50 through.

MARTIN DE LIN.
